S. E. ALLEN

SPOUT MEASURE

Filed Aug. 13, 1923

Fig. 2.

INVENTOR:
SCOTT E. ALLEN,
BY

Graham & Davis
ATTORNEYS.

UNITED STATES PATENT OFFICE.

SCOTT E. ALLEN, OF LOS ANGELES, CALIFORNIA, ASSIGNOR TO SWINGSPOUT MEASURE CO., A CORPORATION OF CALIFORNIA.

SPOUT MEASURE.

Application filed August 13, 1923. Serial No. 657,026.

To all whom it may concern:

Be it known that I, SCOTT E. ALLEN, a citizen of the United States, residing at Los Angeles, in the county of Los Angeles and 5 State of California, have invented a new and useful Spout Measure, of which the following is a specification.

My invention relates to spout measures.

The general object of my invention is to 10 provide a manually operated valve and rigid swing spout measure which will be highly accurate and efficient in use, and particularly useful at automobile oil service stations for filling automobile crank case reservoirs.

15 Further objects and advantages will be made evident hereinafter.

Referring to the drawing which is for illustrative purposes only,

20 Fig. 1 is a vertical longitudinal section of my invention.

Fig. 2 is a horizontal section thereof taken on line 2—2 of Fig. 1.

25 In the drawing, 1 indicates a receptacle casing in which is secured a false inverted conical bottom 2 above the lower end of said casing, a measuring receptacle 3 being formed above said bottom and an outlet conduit hood 4 being formed below said bottom. The upper end 5 of the casing 1 is 30 turned inwardly and downwardly to provide a measuring edge 6 below the top of the receptacle 3 and to prevent spilling of oil out of the top of said receptacle.

35 The bottom 2 is provided with a central outlet 7, and an outlet conduit 8 is secured at its upper end centrally to the underside of said bottom in communication with said outlet and extends downwardly at an incline through the hood 4 and outwardly 40 through the front of the casing 1. The conduit 8 is formed near its outer end in front of said casing with an external annular bead 9.

45 A rigid metal swing spout 10 is constructed with a tapered spout member 11 and a cylindrical spout head 12, in communication with said spout member, the axis of said head extending at right angles to the axis of said spout member. The front end of the 50 spout head 12 is closed by a wall 13, while the rear end of said head is open and is turnably telescoped over the front end of conduit 8, there being an annular external bead 14 formed on the inner end of said head which fits over the bead 9 on said con-

duit, whereby the spout 10 is prevented from pulling off said conduit.

The bottom 2 is formed with a valve seat 15 about its outlet 7, upon which a valve 16 normally seats to close said outlet. The 60 valve 16 is secured to one end of a lever 17, extending rearwardly from said valve, and pivoted at 18 in lug 19 upstanding from the bottom 2, the other end of said lever being secured to the lower end of a vertical rod 65 20 within the receptacle 3 near the rear wall thereof, the upper end of which rod extends through an aperture 21 in the upper end 5 of the casing 1 and carries a head 22, there being a spring 23 interposed between said 70 end 5 and said head which normally holds said rod in its uppermost position and said valve 16 on its seat 15, closing the outlet 7 so that no oil may escape out of the receptacle 3 through the conduit 8 and spout 75 10. A handle 24 is secured to the back of the casing 1 for holding the measure.

In operation, the valve 16 being closed and the spout 10 extending upwardly as shown in full lines in Fig. 1, the measuring 80 receptacle 3 is filled with oil up to the edge 6, which measures a definite amount of oil, such as a quart. The spout 10 is then turned down vertically as shown in dotted lines in Fig. 1 and inserted into the oil inlet 85 leading to the automobile crank case reservoir. The operator, with the thumb of his hand holding the measure by the handle 24, presses downwardly on the head 22, whereby the valve 16, through rod 20 and lever 17, 90 is lifted off its seat 15 and the outlet 7 opened. The measured oil in the measuring receptacle 3 then flows out of said receptacle through said outlet conduit 8 and spout 10 into said crank case reservoir. 95

I claim as my invention:

1. A device of the character described, comprising: a cylindrical receptacle having its upper rim curved inwardly and downwardly to form a measuring indicator and a non-splash element, the bottom of said receptacle being disposed above the lower end of the receptacle wall, being of conical shape and having a discharge opening in the center thereof; a single unit stationary discharge 100 conduit leading from said opening in the bottom at a lateral incline through the wall of the receptacle below the bottom thereof; an annular bead on the outer end of said conduit; a non-flexible swing spout telescop- 110

- ing the outer end of said conduit, said swing spout being provided with an annular recess closely engaging said annular bead and said swing spout being adapted to be swung 5 in a plane parallel to the wall of said receptacle and on an axis diametric to the axis of said receptacle; a valve adapted to close said opening; a pivotally mounted arm extending from said valve for opening and closing same; and a vertical slidable actuating stem adjacent the wall of said receptacle pivoted to one end of said arm and extending at its upper end through a guide hole in the curved upper rim of said receptacle, said 10 actuating stem being provided at its upper end with a thumb piece.
2. A device of the character described, comprising: a cylindrical receptacle having its upper rim curved inwardly and downwardly to form a measuring indicator and a non-splash element, the bottom of said receptacle being disposed above the lower end of the receptacle wall, being of conical shape and having a discharge opening in the center thereof; a single unit stationary discharge conduit leading from said opening in the bottom at a lateral incline through the wall 15 of the receptacle below the bottom thereof; an annular bead on the outer end of said conduit; a non-flexible swing spout telescoping the outer end of said conduit, said swing spout being provided with an annular recess closely engaging said annular bead and said swing spout being adapted to be swung in a plane parallel to the wall of said receptacle 20 and on an axis diametric to the axis of said receptacle; a valve adapted to close said opening; a pivotally mounted arm extending from said valve for opening and closing same; a vertical slidable actuating stem adjacent the wall of said receptacle pivoted to one end of said arm and extending at its upper end through a guide hole in the curved upper rim of said receptacle, said 25 actuating stem being provided at its upper end with a thumb piece; and a compression spring interposed between said thumb piece and said curved rim and enclosing said stem, the action of said spring being adapted to normally retain the valve in closed position. 30
- In testimony whereof, I have hereunto set my hand at Los Angeles, California, this 6th day of August, 1923.
- SCOTT E. ALLEN.
